DESIGN FOR A PORTABLE FIRE EXTINGUISHER OR SIMILAR ARTICLE

Daniel Mapes, West Caldwell, N. J.

Application March 9, 1948, Serial No. 145,004

Term of patent 14 years

(Cl. D16—2)

To all whom it may concern:

Be it known that I, Daniel Mapes, a citizen of the United States, residing in West Caldwell, in the county of Essex, in the State of New Jersey, have invented a new, original, and ornamental Design for a Portable Fire Extinguisher or Similar Article, of which the following is a specification, reference being had to the accompanying drawing, forming a part thereof.

fire extinguisher or similar article, embodying my new design; and

Figure 2 is a top plan view thereof.

I claim:

The ornamental design for a portable fire extinguisher or similar article, substantially as shown.

DANIEL MAPES.
